DEVICE FOR USE IN EXAMINING TEETH

Herman L. Frank, Buffalo, N. Y.

Application August 21, 1941, Serial No. 407,765

1 Claim. (Cl. 240—2.18)

This invention relates to improvements in devices or implements for use in connection with the inspection or examination of teeth.

Dentists are usually provided with implements of various types by means of which they may examine the teeth of patients, but such instruments are usually not available to the general public. Consequently, individuals can not readily examine their own teeth to determine whether the same are clean, or to dislodge foreign matter therefrom, or to determine whether or not the services of a dentist are required.

One of the objects of this invention is to provide a relatively simple and inexpensive implement or device which may be easily used by an individual in conjunction with a mirror for the purpose of inspecting or examining his own teeth. Another object of this invention is to provide an implement of this type with means for illuminating the interior of the mouth and with a mirror or reflector which may be inserted into the mouth to examine the inner surfaces of the teeth. A further object of this invention is to provide an implement of this kind which may be alternatively used either with a mirror or reflector for examining the inner surfaces of the teeth or with a cheek extending or displacing member which may be used in either side of the mouth for examining the outer surfaces of the teeth. Other objects will appear from the following description and claim.

In the accompanying drawing:

Fig. 1 is a perspective view of a tooth-examining device embodying this invention and having a reflector or mirror arranged thereon.

Fig. 2 is a perspective view of the mirror detached from the device or implement.

Fig. 3 is a perspective view of that end of the implement which is inserted into the mouth and showing attaching means for applying a mirror or a cheek-extending member thereto.

Fig. 4 is a transverse sectional elevation taken approximately on line 4—4, Fig. 1.

Fig. 5 is a perspective view of the illuminating end of the device showing a cheek-extending member applied thereto.

Fig. 6 is a perspective view of the cheek-extending member detached from the implement.

Fig. 7 is a sectional, perspective view of a human mouth showing a portion of my improved implement inserted therein, with a cheek-extending member secured thereto.

Fig. 8 is a perspective view of my device or implement showing the same inserted into a mouth for examination of the teeth.

Fig. 9 is a sectional elevation, taken on line 9—9, Fig. 4.

My improved device or implement includes a handle portion 15 of any suitable or desired construction, and which is preferably made hollow so as to form a housing for a dry cell or battery for supplying electric current to operate a light bulb 16 for illuminating the interior of a mouth. The handle, for example, may have a removable cap 17 on the end thereof through which a dry cell or battery 18 may be inserted into or removed from the handle. The other end of the handle 15 terminates in a stem portion 20 which is preferably tubular in form and terminates in a bulb-like enlargement 21 in which a socket for the electric light bulb 16 is provided. The handle and stem, together with its enlargement 21, may be made of any suitable or desired material. These three parts may, for example, be made integral or formed separately of the same material, or the handle may be made of metal while the stem and enlargement 21 thereof are made of a plastic or non-conducting material which can be easily cleansed or sterilized. As indicated in the drawing, the stem 20 and its enlargement 21 are made in one piece, of a plastic or insulating material, and are molded so that the usual threaded light socket 23 is suitably embedded or secured therein, and the current conducting tip 24 with which the tip of the light bulb 16 contacts may also be embedded in this enlargement 21. Suitable conductors 25 and 26 connect respectively with the socket 23 and the current-conducting tip 24 and extend through the hollow stem 20 for connection with the dry cell or battery 18 in any usual or suitable manner through a switch 28. Since these connections and the switch may be of any suitable or desired form, such as are commonly used on flashlights of various types, they are not herein shown in detail. It will also be obvious that if the stem 20 and its enlarged end 21 are made of metal or other electrical conducting material, the stem itself may constitute one of the conductors, as is common practice in flashlights.

All of the parts thus far described do not of themselves constitute a part of this invention and may be of any other suitable or desired construction.

Preferably, the extension or enlargement 21 of the stem 20 is formed in such a manner that the electric light bulb 16 will have its axis arranged transversely of the axis of the stem 20, so as to facilitate the use of the device for illuminating the interior of a mouth. Means are

provided on the device for removably supporting either a mirror 30 on the device or a cheek-extending member 40. In order to be of maximum usefulness, it is desirable to have the reflector or mirror 30 arranged approximately in the position shown in Fig. 1, so that the light bulb 16 extends slightly beyond the reflecting face of the mirror 30, and to removably hold the mirror in place on the device, so that it may be removed therefrom and replaced by the cheek-extending member 40, since the mirror or reflector 30 is necessary for the inspection or examination of certain inner surfaces of the teeth while the cheek-extending member is essential for use in connection with the inspection of other portions or surfaces of the teeth. Any suitable or desired connection or securing means may be employed for readily attaching either the mirror or the cheek-extending member to the device. In the construction shown for this purpose, the outer end of the bulb-like enlargement 21 of the device is provided with an outwardly extending collar or annular supporting member 31, the peripheral portion of which is substantially cylindrical in form and the inner edge of which is so formed as to permit the light bulb 16 to be secured in its socket and to extend outwardly beyond the collar.

The reflector or mirror is provided with a part which may engage the collar 31, preferably frictionally, so that the mirror may be readily placed on or removed from this collar. This may be effected in any suitable or desired manner, and in the construction illustrated, the mirror 30 is provided with a circular aperture or hole 33 which is of such diameter that it will fit about the outer periphery of the collar 31. Consequently the mirror or reflector 30 may be easily positioned on the device, as indicated in Figs. 1 and 4. When the mirror has been positioned on the device or implement, the same may be inserted into the mouth at a slight inclination, as shown in Fig. 8, whereupon the inner surfaces of the teeth of the upper jaw may be clearly seen in the mirror, as well as a part of the upper palate or roof of the mouth. The light bulb 16 is so arranged with reference to the mirror that its light is directed mainly against the roof of the mouth and the inner surfaces of the teeth, so that the mirror will very plainly reflect the illuminated surfaces. If a person is using this device himself, he must of course stand before another mirror, such for example, as a wall mirror, so that through such mirror (not shown), he may see the reflections of the teeth in the mirror 30.

While the mirror 30 is shown flat in form, so as to reflect the teeth without enlargement, yet it will be obvious that if desired, the mirror 30 may be of any other shape and may be formed to show enlarged or magnified images of the teeth.

When the implement is used in the manner indicated, the stem 20 and the lower portion of the enlargement 21 thereof may be used as tongue depressors so that the tongue will not interfere with the proper examination or inspection of the teeth of the upper jaw. As a rule, no means need be provided for the inspection of the inner surfaces of the teeth of the lower jaw, but if desired, it is of course obvious that my improved implement or device may be inverted or tilted at an angle from the position shown in Fig. 8, so that the mirror 30 will reflect the inner surfaces of the teeth of the lower jaw or, if

desired, the mirror may be removed from the device so that the device may be used merely for illuminating the teeth of the lower jaw so that they can be seen through a wall or hand mirror.

In order to enable a person to inspect the outer surfaces of the back teeth of the upper and lower jaws, the implement is inserted into either side of the mouth between the adjacent surfaces of the teeth and the cheek. Since the cheeks ordinarily are spaced quite closely or in contact with the outer surfaces of the teeth, I have found it very desirable to use a cheek-extending member in connection with my improved teeth-inspecting device so that a cheek may be held far enough away from the teeth to permit an adequate view of the outer surfaces of the teeth. The cheek-extending member may be of any suitable or desired shape and material, being shown of a somewhat triangular shape in the accompanying drawing merely by way of example. Since some of the pressure may be exerted by the cheek against the cheek-extending member, it is also desirable to secure this member to the implement more securely than the mirror or reflector 30. I have, consequently provided means for securely and removably mounting the cheek-extending member on the collar 31. For this purpose, the cheek-extending member is provided with an annular band or sleeve 41 which may be connected with the cheek-engaging portion 40 thereof, by means of an arm or neck 42. The annular sleeve 41 is preferably also provided on its inner face with an inwardly extending lug or projection 43 which is formed to enter into a groove 45 formed on the collar 31. This groove preferably extends about half-way around the collar and a small groove 46 extends upwardly from an intermediate portion of the groove 45 to the upper edge of the collar 31. Consequently, the sleeve of the cheek-extending member may be positioned on the collar 31 by first passing the lug 43 downwardly in the upright groove 46 until it enters the circumferential groove 45. The sleeve 41 may then be turned in either direction to position the cheek-extending member at either side of the light bulb 16. In order to move this cheek-extending member from one side to the other of the light bulb, the lug 43 moves from one end of the groove 45 to the other end thereof in the particular construction shown. This construction serves to hold the cheek-extending member securely and releasably on the implement, but any other means may be employed for this purpose if desired.

By the use of the device with the cheek-extending member mounted thereon, the cheek may be extended or pushed laterally away from the adjacent teeth when the implement is inserted into a side of the mouth while the stem 20 is in substantially upright position, as shown in Fig. 7. The light will then shine directly on the outer surfaces of the teeth so that the same may be easily seen in a wall or hand mirror if the user is examining his own teeth. Any person examining the teeth of another person can, of course, see the outer surfaces of the teeth directly, by using the implement without a mirror.

By means of the implement shown, any person may easily inspect or examine his teeth to make sure that they are thoroughly cleaned and that no particles of food or foreign matter remain between the teeth. By thoroughly cleaning the teeth, decay and deterioration thereof may, to a large extent, be avoided. Furthermore, if a defect or cavity occurs in the teeth, the user of the

device may detect the same in ample time so that a comparatively small cavity or filling may be sufficient to remedy the defect. While the device is primarily intended for use by individuals for examining their own teeth it will be obvious that the device may also be used by dentists, for example, for the purpose of showing to their patients the work which they have done or should do on the teeth.

While I have shown a dry battery as a source of power to avoid any possibility of giving the user a shock, yet any other source of electricity for the light bulb may be provided if desired.

I claim:

A device for use in examining teeth, including a hollow handle portion adapted to receive a battery, a hollow stem extending outwardly from said handle, an electric light socket at the end of said stem, a conductor in said stem extending from said socket to said battery, a collar arranged about said socket, and a mirror having a circular hole formed therein into which said collar may enter for supporting said mirror on said stem substantially parallel thereto.
